US00D594454S

(12) **United States Design Patent**
Honda

(10) **Patent No.:** **US D594,454 S**
(45) **Date of Patent:** **** Jun. 16, 2009**

(54) **PORTABLE INFORMATION TERMINAL
UNIT**

(75) Inventor: **Tatsuya Honda**, Yokohama (JP)
(73) Assignee: **Kabushiki Kaisha Toshiba**, Tokyo (JP)
(**) Term: **14 Years**
(21) Appl. No.: **29/303,997**
(22) Filed: **Feb. 22, 2008**
(30) **Foreign Application Priority Data**

Sep. 21, 2007 (JP) 2007-025756

(51) **LOC (9) Cl.** **14-02**
(52) **U.S. Cl.** **D14/345**

(57) **CLAIM**

The ornamental design for a portable information terminal unit, as shown and described.

DESCRIPTION

FIG. 1 is a front perspective view of a portable information terminal unit showing my new design;

FIG. 2 is a perspective view with the keyboard in a drawn out state thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a front view with the keyboard in a drawn out state thereof; and,

FIG. 10 is a right side view with the keyboard in a drawn out state thereof.
